US00D680879S

(12) **United States Design Patent**
Gershune et al.

(10) **Patent No.:** **US D680,879 S**
(45) **Date of Patent:** **** Apr. 30, 2013**

(54) **DISPENSER**(75) Inventors: **Jeffrey Allan Gershune**, Chicago, IL (US); **Dan Kraemer**, Chicago, IL (US)(73) Assignee: **S.C. Johnson & Son, Inc.**, Racine, WI (US)(**) Term: **14 Years**(21) Appl. No.: **29/391,000**(22) Filed: **May 2, 2011**(30) **Foreign Application Priority Data**

Nov. 3, 2010 (EM) 001242937

(51) **LOC (9) Cl.** ..... **09-01**(52) **U.S. Cl.**USPC ..... **D9/689**(58) **Field of Classification Search** D9/500-505, D9/682-694, 516-575, 434-454, 719, 723-729; 222/153.01, 153.03, 153.04, 153.09, 153.11-153.14, 222/182, 631, 635, 321.7-321.9, 372, 373, 222/378, 379, 383.1, 384-386, 398, 400.7, 222/400.8, 401, 402.1-402.25

(57) **CLAIM**

The ornamental design for a dispenser, as shown and described.

DESCRIPTION

FIG. 1 is a top, front and right isometric view of the dispenser showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines are included for the purpose of illustrating portions of the dispenser that form no part of the claimed design.

1 Claim, 4 Drawing Sheets# US D680,879 S
